UNITED STATES PATENT OFFICE.

ORIN A. HANFORD, OF PARIS, MAINE.

DESIGN FOR A RIM FOR WHEELS.

SPECIFICATION forming part of Design No. 27,150, dated June 1, 1897.

Application filed September 17, 1896. Serial No. 606,182. Term of patent 7 years.

To all whom it may concern:

Be it known that I, ORIN A. HANFORD, a citizen of the United States, residing at West Paris, in the county of Oxford and State of Maine, have invented and produced a new and original Design for Rims for Wheels, of which the following is a specification, reference being had therein to the accompanying drawings.

10 Figure 1 of the accompanying drawings is a perspective view, partially broken away in order to indicate the cross-sectional effect, of a rim for wheels embodying my design. Fig. 15 2 is a perspective view of a short section of said rim, showing the inner surface thereof as also the cross-sectional shape, and also showing the essential features of my design from another point of view.

My design comprises a ring or wheel shaped body the essential features of which are the convex or rounded swells or side portions 1 1, the well-defined shoulders or prominences 2

2, rising boldly from the surface of the said side swells 1 1 at the inner edges thereof, and the ogee curves 3 3, extending inwardly from the said shoulders and meeting to form the rounded crest 4, as will be perceived. The said rounded crest or middle portion is in effect supported at a distance out of the general curve of the side swells 1 1 by the height 30 of the parallel prominences 2 2. The said prominences present a marked break in the convexity of the rim and in side view constitute a conspicuous feature of the design.

I claim—

35 The design for a rim for wheels, substantially as shown and described.

In testimony whereof I affix my signature in presence of two witnesses.

ORIN A. HANFORD.
